Henry G. Hubbard and Alfred G. Hubbard, of Buffalo, N.Y.

Letters Patent No. 2186 Dated Oct. 10-1865.

Design for a Cook's Stove.

The schedules referred to in these Letters Patent and making part of the same.

shall also be at any concern;

Be it known that we, Henry G. Hubbard, and Alfred G. Hubbard, of the City of Buffalo, in the County of Erie and State of New York, have invented or produced a new and original design for a cooking stove, called the "Elector," and we do hereby declare that the following is a full and exact description of the same, reference being had to the accompanying photograph and the letters of reference marked thereon.

A is the large oven door.

B is the small oven door.

C is the end or fire door.

What we claim as our invention and desire to secure by Letters Patent is-

The design and configuration as represented in the accompanying photograph.
